UNITED STATES PATENT OFFICE

THOMAS H. SYMINGTON, OF BALTIMORE, MARYLAND, ASSIGNOR TO T. H. SYMINGTON & SON, INC., OF BALTIMORE, MARYLAND, A CORPORATION OF MARYLAND

LATERAL-MOTION ROLLER ASSEMBLY

Application filed July 12, 1928. Serial No. 292,187.

The invention relates to railway car trucks, particularly that type provided with rollers beneath the end portions of the truck bolster for the purpose of permitting lateral motion of the truck bolster and body bolster as a unit with respect to the truck side frames.

It is a common practice to provide rollers located between the end portions of the truck bolster and an element or seat engaged upon the truck springs. Two, three or possibly more rollers may be used at this location for the purpose of facilitating lateral motion of the truck bolster. In actual practice it has been discovered that in case of derailment of a truck the rollers fall out and are consequently lost resulting in obvious disadvantages on account of the necessity for replacement and the expenditure involved therein.

It is with the above facts in view that I have devised the present invention which has for its general object the provision of a roller assembly having means whereby the rollers are positively retained in place so that loss thereof under any circumstances will be prevented.

An important object of the invention is to provide a roller assembly in which the roller retaining means is removable in case it is desired to replace a broken or worn roller or to disassemble the parts for any other reason.

Another object of the invention is to provide an assembly in which the ordinary bolster may be used without change, or in which the bolster may be modified so as to accommodate the roller retaining means, the co-operation of the retaining means with the bolster preventing any displacement of the former in service, it being necessary, in such an instance, to remove the entire assembly from the truck before the retaining means be detached for liberating the rollers.

A further object of the invention is to provide a lateral motion roller assembly in which the retaining means for the rollers may be formed as separate elements simply attached, or in which the retaining means may form an integral part of the roller seat member, depending upon the will of the manufacturer and the contemplated cost of production.

An additional object is to provide an assembly of this character which will be simple and inexpensive to make, easy to assemble, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a view partly in elevation and partly in section showing a truck bolster and roller bearing assembly constructed in accordance with one form of the invention.

Figure 2 is a detail perspective view of the roller assembly removed from the truck.

Figure 3 is a side elevation of one form of roller.

Figure 4 is a view partly in elevation and partly in section showing a modified roller.

Figure 5 is a perspective view of the assembly detached and illustrating the retaining means as differently located.

Figure 6 is a detail longitudinal or vertical section through one end of a bolster modified for use in connection with the modified type of assembly shown in Figure 5.

Referring more particularly to the drawing, the numeral 1 designates a truck side frame having the usual window opening 2 which receives the reduced end portion 3 of the truck bolster 4. The bolster is shown as having a center bearing 5 receiving the center plate 6 on the body bolster 7 which in the present instance is represented as provided with depending bearing elements 8 cooperating with side bearings 9 on the truck bolster. The side bearing structure does not enter into the present invention but is shown simply as being conventional. The numeral 10 designates the spring plank which supports the spring nest 11 illustrated diagrammatically, the nest including any desired number of helical or other springs, as is customary, located between the spring caps 12. These springs support the truck bolster and it is between the springs and the bolster that

the lateral motion roller assembly is mounted.

In carrying out the invention, I provide an assembly which includes a seat member indicated generally at 13 which is preferably 5 of general rectangular shape and of a size to fit within the window opening 2, the member having spaced outstanding ribs 14 engaging against the opposite sides of the pedestal guides or sides of the window opening. 10 The underside of the member 13 is preferably recessed or formed with a peripheral flange 15 so as to receive the upper spring cap 12. The top surface of the seat member 13 is shown as formed with similar curved portions 16 which may, if desired, have the same shape as disclosed in my co-pending application Serial No. 292,186 filed July 12, 1928, though this is not necessary. The rollers 17 are mounted on the curved surfaces 16 15 and in turn bear against curved surfaces 18 on the underside of the bolster. The preferred number of rollers is two though I do not wish to be limited in this respect as more may be employed if desired. It is preferable 20 that the underside of the bolster be offset upwardly as illustrated so as to permit the use of rollers of greater diameter than would otherwise be possible without changing the dimensions of the other parts. While 25 the surfaces 16 and 18 are shown and described as preferably curved it will be understood that they might be inclined instead if such should be found desirable for any reason and it is contemplated that they may 30 be made in this shape or that there may be a combination of curved and inclined surfaces, for instance as set forth in said co-pending 35 application above identified.

The principal feature of the invention is 40 the provision of means for retaining the rollers in place with respect to the seat member 13 so that the entire assembly will constitute a unit capable of being handled as such without disconnection or disassociation of the 45 parts, this feature being of prime importance in preventing loss of the rollers in case of derailment of a car. This result may be accomplished in various ways and in Figures 1 and 2 I have shown the rollers as provided 50 at their ends with reduced extensions or trunnions 19 engaged by metal straps or bands 20 which extend the length of the seat member 13 in embracing relation thereto with their 55 end portions curved downwardly at 21 and terminating in hooks 22 engaged beneath the flanges 15.

Instead of being formed with the trunnions 19, the rollers may be constructed as 60 shown in Figure 4 wherein the roller 17^a is disclosed as having a shaft 23 extending therethrough and projecting beyond the ends thereof. Whether the shaft be loose or tight is immaterial.

In Figures 5 and 6 I have illustrated a 65 modification in which the rollers 17^b need

not be provided with either the trunnions 19 or the shaft 23 inasmuch as use is made of a single retaining strap or band 24 similar to the bands 20 and hooked under the flange 15 as above described. This single band is preferably located at the center of the seat member 13 and bears directly upon the rollers themselves. In this instance the underside of the bolster end must be grooved as shown at 25 for the accommodation of the retaining strap or band and it will be observed that when the band is engaged within this groove it cannot become displaced laterally, that is to say lengthwise of the rollers. It cannot become displaced in the other direction as the hooked ends are engaged beneath the flanges 15.

The assembly is installed within the truck in substantially the same manner as one unprovided with retaining means for the rollers and it is obvious that in operation the rollers will act in identically the same manner as those in other devices of this general type. It is well known that when there is any tendency of the car body to move sideways, as for example when rounding a curve or when passing over a low spot in a rail, the truck and body bolsters will, as a unit, move laterally with respect to the truck side frames, the surfaces 16 and 18 cooperating with the rollers to permit this movement and at the same time to effect a lifting action which neutralizes or at least partially counterbalances the tendency of the car to move laterally. The underlying theory relating to the provision of lateral motion devices is so well known that further detailed explanation of the operation is thought to be superfluous. The principal feature in the present structure is that even though a truck be derailed the rollers cannot work out and become lost. Clearly this is bound to effect a saving in maintenance and avoid a great deal of annoyance as well as loss of time. It is believed that the construction, operation and advantages will be readily apparent to one skilled in the art without further explanation.

While I have shown and described preferred embodiments of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a railway car truck including a truck bolster and supporting springs therefor, a seat member mounted upon the springs, rollers interposed between the seat member and the underside of the bolster, and means em- 130

bracing the seat member transversely of the rollers for retaining the rollers upon the seat member.

2. In a railway car truck including a truck 5 bolster and supporting springs therefor, a seat member mounted upon the springs, rollers interposed between the seat member and the underside of the bolster, and means embracing the seat member and continuously overlying the rollers for retaining the rollers upon the seat member.

3. In a railway car truck including a truck 10 bolster and supporting springs therefor, a seat member mounted upon the springs, rollers interposed between the seat member and the underside of the bolster, and means for retaining the rollers upon the seat member, said means being received within the bolster.

4. In a railway car truck including a truck 15 bolster and supporting springs therefor, a seat member mounted upon the springs, rollers having their axes transverse to the bolster interposed between the seat member and the underside of the bolster, and means for retaining the rollers upon the seat member, said means comprising a metal band overlying the rollers and having its ends embracing the seat member.

5. In a railway car truck including a truck 20 bolster and supporting springs therefor, a seat member mounted upon the springs, rollers interposed between the seat member and the underside of the bolster, and means for retaining the rollers upon the seat member, said means comprising a metal band overlying the rollers and having its ends connected with the seat member at the underside thereof.

6. In a railway car truck including a truck 25 bolster and supporting springs therefor, a seat member mounted upon the springs, rollers interposed between the seat member and the underside of the bolster, and means for retaining the rollers upon the seat member, said means comprising a metal band overlying the rollers and terminating in hooks engaging beneath the edges of the seat member.

7. In a railway car truck including a truck 30 bolster and supporting springs therefor, a seat member mounted upon the springs, rollers interposed between the seat member and the underside of the bolster, and means for retaining the rollers upon the seat member, said means comprising a metal band overlying the rollers and terminating in means engaging beneath the seat member.

8. In a railway car truck including a truck 35 bolster and supporting springs therefor, a seat member mounted upon the springs, rollers interposed between the seat member and the underside of the bolster, and means for retaining the rollers upon the seat member, said means comprising a metal band located 40 above and extending transversely of the roll-

ers with its ends detachably connected beneath the edges of the seat member.

9. In a railway car truck including a truck 45 bolster and supporting springs therefor, a seat member mounted upon the springs, rollers interposed between the seat member and the underside of the bolster, and means for retaining the rollers upon the seat member, said means comprising a metal band located above and extending transversely of the rollers with its ends detachably connected beneath the edges of the seat member, the bolster having a longitudinal groove in its underside accommodating said band.

10. A roller bearing assembly comprising 50 a seat member adapted to rest upon the spring nest in a railway truck of the lateral motion type, rollers mounted on said seat member, and means engaging said rollers and extending transversely thereover for preventing disengagement thereof from the seat member.

11. A roller bearing assembly comprising a seat member adapted to rest upon the spring 55 nest in a railway truck of the lateral motion type, rollers mounted on said seat member, means engaging said rollers for preventing disengagement thereof from the seat member, said seat member having a depending peripheral flange, and said means being detachably connected with said flange.

12. A roller bearing assembly of the character described comprising a seat member having flanges at its opposite ends, rollers mounted on the seat member, and a metal band engaging portions of the rollers and terminating in hooks engageable beneath said flanges.

13. A roller bearing assembly for use in a lateral motion truck, comprising a seat member adapted to rest upon a truck spring nest, a plurality of rollers mounted on said seat member and adapted to cooperate with the truck bolster, and means on said seat member received within the bolster and overlying portions of the rollers for maintaining the same against disengagement from the seat member.

14. In a railway car truck including a truck 105 bolster and supporting springs therefor, a seat member mounted upon the springs, rollers interposed between the seat member and the underside of the bolster, and means embracing the seat member and overlying the axes of the rollers for retaining the rollers upon the seat member.

In testimony whereof I affix my signature.
THOMAS H. SYMINGTON.
